CLAIM

The ornamental design for a hair microanalyzer, as shown and described.

DESCRIPTION

FIG. 1 is a perspective view of the front, side and top of the hair microanalyzer showing my new design;

FIG. 2 is a front elevational view thereof; and

FIG. 3 is a right side elevational view thereof, the left side being substantially a mirror image of the right side shown herein except for the omission of the knob.

The rear of the microanalyzer is substantially flat and unornamented.
